UNITED STATES PATENT OFFICE.

ALEXANDER ADAMSON, OF AKRON, OHIO.

COLLAPSIBLE CORE.

1,007,626.

Specification of Letters Patent. Patented Oct. 31, 1911.

Application filed February 20, 1911. Serial No. 609,693.

To all whom it may concern:

Be it known that I, ALEXANDER ADAMSON, a citizen of the United States, residing at Akron, in the county of Summit and State of Ohio, have invented new and useful Improvements in Collapsible Cores, of which the following is a specification.

This invention relates to improvements in collapsible cores for manufacturing the outer-shoes of double-tube pneumatic-tires, and the object thereof is to provide a collapsible-core which may be quickly assembled or collapsed, the invention contemplating the provision of a plurality of segment-shaped members, which, when united, will form an annular core-body for imparting to the interior of a tire-shoe during the manufacture thereof, the proper shape to receive the inner inflatable tube, the invention more particularly residing in the means whereby the various segment-shaped members constituting the body-portion of the core are temporarily united.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the claims hereunto appended.

In the drawings in which similar reference numerals indicate like parts in the different figures, Figure 1, is a plan of a ring core embodying this invention; Fig. 2, is a longitudinal, central sectional view of two segment-shaped members forming a portion of an annular core body, illustrating the means by which the abutting ends of the two members are detachably united. Fig. 3, is a sectional view on line X, of Fig. 1; Fig. 4, is a side elevation of the outer face or tread-forming surface of a portion of a core embodying this invention; and, Fig. 5, is a detail of a portion of the mechanism used for detachably uniting the segment-shaped members together.

The ring-core is constructed of a plurality of segment-shaped members, which, when united together by means to be herein-after described, constitute an annulus, the outer portion of which is shaped to impart

the desired configuration to the inner wall of a tire-shoe manufactured thereon. These segment-shaped members are designated in the drawings by the reference numerals 1, 2, 3, and 4, and are designed to be assembled with their ends arranged in abutting relation to form, when so assembled, a complete annulus, and each segment is preferably provided with an inwardly-extending flange 60 5. The means for uniting the various segments together are all similar and hence a description of one is deemed to be sufficient. It will be assumed that the description which follows refers to the uniting of segments 3 and 4. 70

In order to secure perfect registration between contiguous segments the abutting ends of the outer or tread-forming portions of the segment-shaped members are provided with alined recesses to receive a key 6 which is preferably secured to one member by some means such as a pin 7, so that as the segment 4 is withdrawn inwardly the key 6 offers no obstacle to its movement. 80 The key 6 secures perfect registration between the outer tread-forming portions of the segments and prevents lateral displacement of one member with respect to the remaining members, and in order to prevent 85 radial displacement of one member with respect to its contiguous member, dowel pins 8 are inserted in openings preferably extending transversely through the flanges of contiguous members at the joint between 90 them.

The locking means for uniting each pair of contiguous segment-shaped members together to form an annular core-body comprises a bolt 9 shiftably mounted in a pair 95 of alined recesses 10 and 11 formed in the abutting portions of contiguous segments. These recesses 10 and 11 are interiorly-shaped to receive the bolt 9 and are of sufficient length to permit the same to be shifted 100 to lock or release coadjacent segments, that is to say, the recess in the segment which carries the bolt is of sufficient length to permit the bolt to be withdrawn from the recess 11 in the coadjacent segment and the recess in the segment 4, is, for instance, of sufficient length to receive the projecting end 105 of the bolt 9 when the latter is forced outwardly from the recess 10. The bolt 9 comprises a main portion 12 preferably cylindrical, from which extends a reduced portion or shank 13, having along one face

thereof a series of gear-teeth 14. Mounted in a threaded opening communicating at right angles with the recess 10 is a threaded shaft 15 the outer end 16 of which is preferably squared to receive a wrench for rotating the shaft and with its opposite end 17 provided with gear-teeth to mesh with the teeth 14 on the bolt 9, so that by rotating the shaft 15 the bolt 9 is shifted inwardly 5 or outwardly as the case may be. The main portion 12 of the bolt 9 is provided on opposite sides with a pair of conical recesses 18 arranged to receive the conical heads of a pair of set-screws 19 which engage therein. 10 15 The set-screws 19 are preferably provided with heads to receive a wrench by which they may be rotated, and these bolts are so positioned with respect to the conical recess 18 that the heads of said set-screws engage 20 opposite walls of the recesses 18 to provide a wedging action tending to draw the abutting ends of contiguous segments into snug engagement with each other. By providing recesses 18 on opposite sides of the bolt 9 25 the latter, may, if one set of recesses become worn, be reversed and the opposite set of recesses used, this being accomplished by unscrewing the shaft 15 sufficiently to permit a partial rotation of the bolt 9. 30 In practice, the various segments are assembled by first alining them by means of the keys 6 after which they are locked together by means of the bolts 9 after which the dowel pins 8 are inserted and a tire-shoe is built on 35 the core-body. The vulcanized tire and core-body embodying this invention are then placed in a suitable mold to be vulcanized, after which, the molds are separated and the cured tire and core removed therefrom. The 40 operator then drives out the dowel-pins 8 and unscrews the set-screws 19 which permits the rotation of the shaft 15 for withdrawing the bolt 9 from the member containing the recess 11 which is then drawn inwardly through the opening in the inner portion of the tire-shoe. In practice, it is customary to first withdraw the segment 1 the 45 shape of which resembles an inverted key-stone after which members 2, 4, and 3 are removed in the order named. 50

I claim:

1. A device of the class described comprising a plurality of segment-shaped members disconnected from and adapted to abut endwise against each other to form a collapsible ring-core, the abutting ends of contiguous members provided with registering recesses, a bolt carried in the recess in one member and adapted to be projected into the recess 55 in the complementary member for temporarily holding said segment-shaped members and means engaging said bolt for locking the latter against movement and simultaneously drawing the opposing ends of co-60 adjacent members toward each other.

2. A device of the class described comprising a plurality of segment-shaped members disconnected from and adapted to abut endwise against each other to form a collapsible ring-core, the abutting ends of contiguous members provided with registering recesses, a bolt carried in the recess in one member adapted to be projected longitudinally into the recess in the complementary member for holding said segment-shaped members temporarily in annular formation and revoluble means in said first member for shifting said bolt, and means for locking the latter against movement while in its extended or operative position. 70 75

3. A device of the class described comprising a plurality of segment-shaped members disconnected from and adapted to abut endwise against each other to form a collapsible ring-core, the abutting ends of contiguous segments being formed with registering recesses, a shiftable bolt in said recesses, means for shifting said bolt while in the recess in one member to cause it to project in the complementary recess, said bolt provided with gear-teeth and a shaft having a portion provided with gear-teeth intermeshing with the teeth on said bolt for longitudinally shifting the latter. 80 85 90

4. A device of the class described comprising a plurality of segment-shaped members disconnected from and adapted to abut endwise against each other to form a collapsible ring-core, the abutting ends of contiguous members provided with registering recesses, a bolt carried by the recess in one member adapted to be projected into the recess in the complementary member for holding said segment-shaped members in annular formation, and means for locking said bolt against 95 movement. 100 105

5. A device of the class described comprising a plurality of segment-shaped members disconnected from and adapted to abut endwise against each other to form a collapsible ring-core, the abutting ends of said members provided with registering recesses, a bolt in the recess of one of said members arranged to be projected into the recess in the complementary member for temporarily holding 110 115 said segment-shaped members in annular formation, means engaging said bolt for shifting it, and a pair of members engaging said bolt for locking said bolt against movement and holding said segment-shaped members snugly together. 120

6. A device of the class described comprising a plurality of segment-shaped members disconnected from and adapted to abut endwise against each other to form a collapsible ring-core, the abutting ends of said segment-shaped members provided with registering recesses, a bolt mounted in the recess in one member and arranged to be shifted to enter and interlock in the recess in the comple- 125 130

mentary member, said bolt provided with a recess, means for shifting said bolt longitudinally and means carried by one of said segments and engaging the recess in said 5 bolt for holding the same against movement.

7. A device of the class described comprising a plurality of segment-shaped members disconnected from and adapted to abut end-wise against each other to form a collapsible 10 ring-core, the abutting ends of contiguous members provided with registering recesses, a bolt mounted in the recess in one member capable of being shifted to enter and interlock in the recess in the complementary 15 member, said bolt provided with a pair of

recesses spaced apart, means for shifting said bolt and means engaging in said last named recesses and carried by each of said segment-shaped members tending to lock said bolt against said longitudinal shifting 20 and force the abutting ends of contiguous members snugly together.

In testimony whereof I have hereunto set my hand in presence of two subscribing witnesses.

ALEXANDER ADAMSON.
